UNITED STATES PATENT-OFFICE.

JOHN W. B. FARIS, OF SKIDMORE, TEXAS.

BARBER'S BOTTLE-HOLDER.

No. 873,933.

Specification of Letters Patent.

Patented Dec. 17, 1907.

Application filed February 18, 1907. Serial No. 357,996.

To all whom it may concern:

Be it known that I, JOHN W. B. FARIS, a citizen of the United States, residing at Skidmore, in the county of Bee and State of Texas, have invented a new and useful Barber's Bottle-Holder, of which the following is a specification.

This invention has reference to improvements in holders for bottles intended for the use of barbers such as are used for holding bay rum, hair tonics, and other fluids, and its object is to provide a holder which when the bottle is removed for use will cause the actuation of a registering device or of a signal 15 or of the two combined.

The invention consists essentially of a bottle provided with a rounded bottom so that it will not remain upright on a flat surface, and a correspondingly shaped receptacle so 20 arranged as to hold the bottle in an upright position. The receptacle is provided with a movable portion in the path of the bottle so that when the bottle is placed in the receptacle this movable portion will be actuated. 25 and through it and suitable connections there will be actuated a register or a signal or both which will indicate that the bottle has been removed for use and replaced after use.

The invention will be fully understood 30 from the following detailed description taken in connection with the accompanying drawings forming part of this specification, in which,

Figure 1 is an elevation, partly in section, 35 of the improved bottle and register-actuating receptacle therefor, the bottle being shown in place; and Fig. 2 is a section through the receptacle in a vertical plane and also showing a portion of the connections from the 40 receptacle to the register or signal.

Referring to the drawings, there is shown a bottle 1 designed to receive bay rum, Florida water, hair tonic, or any other liquid preparation used by barbers, and this bottle 45 may have the usual long neck 2 and cap 3 from which latter the liquid is expelled in a fine stream or spray.

The body 1 of the bottle is made spherical in shape as shown, or the upper portion of 50 the bottle may be made any shape desired, while the lower portion 4 of the bottle is made hemispherical or elliptical or otherwise rounded so that it will not remain upright

upon a flat surface but must be placed in a suitable receptacle. About midway the body 55 of the bottle is formed with a circumferential flange 5, the purpose of which will presently appear.

Secured upon a suitable base 6 there is a hemispherical, elliptical or otherwise rounded 60 bowl 7 on the top of a suitable stem 8 rising from a foot 9 fast on the base plate 6.

The bowl 7 with the stem 8 and foot 9 may be made of glass or metal or any other material suitable for the purpose, and in 65 order to protect the bottle from harm when placed in the bowl, the latter is provided with a soft rubber lining 10, or this lining may be made of felt or any other soft material, and its upper edge 11 is carried over the upper 70 edge of the bowl 7 so that when the bottle 1 is placed in the bowl the flange 5 will rest upon this overlapping portion of the soft lining as on a ledge, and the flange 5 will thereby serve to maintain the bottle in an upright 75 position in the receptacle.

Extending vertically through the base 6 there is a passage 12 matching another passage 13 in the foot 9, and this passage 13 meets a larger vertical passage 14 extending 80 upward through the stem 8 and opening into the bowl 7 at its lowermost point through a perforation 15 in the soft lining of the bowl. Through these several passages there extends a rod 16 terminating at the upper end in a 85 head 17 of such diameter as to fit snugly but not tightly within the large portion 14 of the passage through the stem and base of the bowl, and this head 17 terminates in a crown piece 18 too large to enter the passage 14 but 90 seating in the perforation 15 in the soft lining of the bowl 7 and in a slight counter-seat 19 around the upper end of the portion 14 of the passage.

The rod 16 leads to a suitable register or 95 signal or combined register and signal of any suitable or desirable type, but which is not shown in the drawings since in itself such register or signal forms no part of the present invention.

It is designed that this bottle and holder therefor shall be attached directly to a barber's chair or to some structure adjacent to the chair. Since the receptacle for the bottle is an upright structure and the rod 16 105 passes downward through the same, it is de-

sirable that the direction of motion of the rod 16 be changed so as to reach the register conveniently located. For this purpose the lower end of the rod 16 may be attached to a rock arm 20 fast on a bracket or standard 21 and another rod 22 secured to the rock arm 20 may transmit the motion imparted to the rod 16 to the register or signal. In order that the parts may be adjusted to adapt the device to the motion of the register, the arm 20 may be slotted as shown at 23 where it is connected to the rod 16 so that the throw of the rod 22 may be adjusted with relation to the extent of travel of the rod 16.

15 Within the portion 14 of the passage through the base and stem of the receptacle the rod 16 is surrounded by a helical spring 24 abutting at one end on the bottom of the portion 14 of the passage and at the other end 20 engaging under the head 17. The tendency of this spring is to hold the rod 16 in an elevated position with the head 17 entering for a distance into the interior of the bowl 7 of the bottle holder. Now, when a bottle is 25 placed in the bowl 7 its weight will cause the rod 16 to be depressed until the crown 18 is seated in the perforation 15 of the soft lining of the bowl; but when the bottle is removed the spring 24 will move the rod upward and 30 again lift the head 17 into the interior of the bowl 7.

The register or signal may be operated by either the removal of the bottle or the replacing of the same in the receptacle, as may be 35 desired.

If it be desired to use the bottle for a preparation used for shampooing, then the register will indicate the number of times that the shampoo preparation has been used, or if the 40 bottle contains hair tonic, then the register will indicate the number of times that such tonic has been used.

If a signal only be used in connection with the bottle receptacle, then this may be operated on the removal of the bottle, or the signal may be so arranged as to be operated both on the removal and the replacing of the 45 bottle, but when a register is used it may be

operated on either the removal or the replacing of the bottle as may be desired.

50

I claim:—

1. In a device of the character described, a bottle having a body with a rounded bottom, a receptacle conforming in shape thereto and receiving the rounded bottom of the 55 body of the bottle, and a longitudinally moving, indicator-actuating means having a normal tendency to enter the receptacle and movable out of the receptacle by the introduction of the bottle therein.

60

2. In a device of the character described, a bottle having a body with a rounded bottom and a circumferential flange therefor, a receptacle for the rounded portion of the bottle and having its upper edge shaped to receive the flange on the bottle, and an indicator-actuating means carried by the receptacle and movable by the bottle.

65

3. In a device of the character described, a bottle, a receptacle therefor, a lining of soft 70 material in the receptacle, and an indicator-actuating means extending into the receptacle through the soft lining and movable out of the receptacle by the introduction of the bottle into the latter.

75

4. In a device of the character described, a bottle having a rounded bottom or base, a circumferential flange at the junction of the rounded base and body of the bottle, a rounded or bowl-shaped receptacle conforming to the rounded base of the bottle, a soft lining for said receptacle overlapping the upper edges thereof and there receiving the circumferential flange on the bottle, a spring-actuated rod carrying a head normally constrained by the spring to enter the receptacle and pushed out of the same by the weight of the bottle, and connections from said rod for operating an indicating device.

80

In testimony that I claim the foregoing as 90 my own, I have hereto affixed my signature in the presence of two witnesses.

JOHN W. B. FARIS.
